(57) **CLAIM**

The ornamental design for a lounge end, as shown.

DESCRIPTION

FIG. 1 is a perspective view of a design for a lounge end according to a first embodiment;

FIG. 2 is a front view thereof;

FIG. 3 is a side view thereof;

FIG. 4 is a rear view thereof; and

FIG. 5 is a top view thereof.

FIG. 6 is a perspective view of a design for a lounge end according to a second embodiment;

FIG. 7 is a front view thereof;

FIG. 8 is a side view thereof;

FIG. 9 is a rear view thereof; and,

FIG. 10 is a top view thereof.
